(57) **CLAIM**

The ornamental design for a modular bracket for overhead storage bins, as shown and described.

DESCRIPTION

FIG. 1 is a perspective view of a modular bracket for overhead storage bins;

FIG. 2 is another perspective view of the modular bracket for overhead storage bins of FIG. 1;

FIG. 3 is a right side view of the modular bracket for overhead storage bins of FIG. 1;

FIG. 4 is a left side view of the modular bracket for overhead storage bins of FIG. 1;

FIG. 5 is a top view of the modular bracket for overhead storage bins of FIG. 1;

FIG. 6 is a bottom view of the modular bracket for overhead storage bins of FIG. 1;

FIG. 7 is a front end view of the modular bracket for overhead storage bins of FIG. 1; and,

FIG. 8 is a rear end view of the modular bracket for overhead storage bins of FIG. 1.

The broken lines in the drawings illustrate portions of a modular bracket for overhead storage bins, which form no part of the claimed design.

1 Claim, 5 Drawing Sheets
